UNITED STATES PATENT OFFICE

HARRY L. BEACH, OF COSHOCOTON, OHIO

DESIGN FOR A RACK FOR TIRES

Application filed October 9, 1930. Serial No. 37,197. Term of patent 14 years.

To all whom it may concern:

Be it known that I, HARRY L. BEACH, a citizen of the United States, residing at Coshocton, in the county of Coshocton and State of Ohio, have invented a new, original, and ornamental Design for a Rack for Tires, of which the following is a specification, reference being had to the accompanying drawings, forming part thereof.

In the drawings, Fig. 1 is a perspective view of the rack, showing my new design.

Fig. 2 is a top plan view thereof, on a reduced scale.

I claim:

The ornamental design for a rack for tires, as shown.

In testimony that I claim the foregoing as my own, I have hereunto affixed my signature.

HARRY L. BEACH.
